CONTROLLING MECHANISM FOR
DISPENSING MACHINES

Henry M. Olsen, Minneapolis, Minn.

Application July 31, 1944, Serial No. 547,390

8 Claims. (Cl. 192—139)

This invention relates to a control device or a coin-controlled device for controlling the operation of a dispensing or similar machine. Such machines are usually made operable by the deposit of a coin and there is an operating member movable by the operator and adapted to be moved through a certain movement or cycle of movement. It is desirable to have a control mechanism which will readily permit this movement or cycle of movement when the proper coin has been deposited, but which will prevent movement when no coin has been deposited and which will prevent further movement when the goods have been properly dispensed.

It is an object of this invention therefore, to provide a control mechanism comprising a rotatable member with means for permitting a certain cycle of movement of said member after which further movement will be prevented.

It is a further object of the invention to provide a control mechanism comprising a rotatable member adapted to move through a certain cycle, a stop member adjacent the same movable to stop and non-stop positions to prevent and permit respectively rotation of said member, a coin-controlled means for moving said member to non-stop position and cam means carried by said rotatable member for moving said stop member to stop position.

It is still another object of the invention to provide a rotatable operated member, a pinion carried thereby, gears meshing with said pinion and adapted to actuate members for operating a machine, a stop member movable adjacent one of said gears to stop and non-stop positions for preventing and permitting rotation of said gear respectively, a coin-controlled means for moving said stop member to non-stop position and means for preventing reverse rotation of said gears.

These and other objects and advantages of the invention will be fully set forth in the following description made in connection with the accompanying drawing in which like reference characters refer to similar parts throughout the several views and in which:

Fig. 1 is a vertical section taken on line 1—1 of Fig. 2;

Fig. 2 is a top plan view of the mechanism with the casing shown in section;

Fig. 3 is a vertical section taken on line 3—3 of Fig. 1;

Fig. 4 is a top plan view of the device, some parts being shown in different positions in dotted lines;

Fig. 5 is a vertical section similar to Fig. 3 showing the parts in a different position; and

Fig. 6 is a vertical section taken on line 6—6 of Fig. 1, said sections being taken as indicated by the arrows.

Referring to the drawings, a device is shown comprising a frame consisting of a member 10 of plate-like form from which extend spacing posts 10a, the ends of which are engaged by the flat side of another plate-like member 11. Member 11 is secured by headed screws 12 extending therethrough and threaded into posts 10a. Members 10 and 11 have bearing bosses 10b and 11b projecting inwardly therefrom in which is journaled a shaft 13 which will be the operating shaft for the device and which will preferably be equipped with an operating handle such as a crank 14. A gear pinion 15 is secured to shaft 13 and as shown substantially midway between members 10 and 11, said pinion having a hub engaging the ends of bosses 10b and 11b. Members 10 and 11 also have bosses 10c and 11c projecting inwardly therefrom in which is journaled a shaft 16. Shaft 16 has secured thereto a gear 17 disposed at one side of and meshing with pinion 15. Gear 17 has a hub engaging the ends of bosses 10c and 11c. Gear 17 has projecting from one side beyond its hub a stop means or projection 17a, said projection having a flat surface at one end disposed in a plane radial to gear 17. Said gear 17 has at its opposite side and beyond its hub a cam 17b, the cam surface of which is on its outer side and extends outwardly from the side of gear 17 at one end of its ends to quite a distance from said gear at its other end. Projection 17a and cam 17b are relatively circumferentially spaced as shown in Figs. 1 and 2. Member 11 is provided with a rectangular slot through which slides a bar 18 rectangular in vertical cross section. Member 10 has a projection or boss 10d extending vertically from boss 10c which is provided with a rectangular slot 10e in which one end of bar 18 slides. Bar 18 is provided with a slot 18a extending from one side thereof in which one side of gear 17 is disposed and through which said gear rotates. Slot 18a is wider than gear 17 so that bar 18 can move lengthwise. When bar 18 is in one position as shown in Fig. 5, which may be called its non-stop position, the projection 17a can pass through slot 18a in the rotation of gear 17 so that rotation of said gear is permitted. When bar 18 is in the position shown in Fig. 3, which is the limit of its movement in one direction, it has moved into the path of projection 17a and will be en-

gaged by the flat surface on one end of projection 17a as gear 17 revolves in one direction. This may be called the stop position of bar 18. Member 11 is provided with a slot to accommodate a gib or key 19 engaging one side of bar 18 and being engaged at its opposite side by a compression coil spring 20 contained in a cylindrical housing 21 secured in member 11. Spring 20 and key 19 exert some friction on bar 18 so that it will not move too freely. It may be stated that shaft 16 will be one of the operating members for the dispensing or similar machine and will be connected to the desired train of mechanism of said machine.

An arm 23 has a lower portion extending along the outer side of member 11 and secured thereto by one set of the screws 12 which are threaded into post 10a. Another similar arm 24 is secured to the outer side of member 11 some distance from arm 23, said latter arm being secured by screws 25. Arms 23 and 24 are provided with bearings at their upper ends in which is journaled a shaft 26. Shaft 26 has secured thereto an arm 27 having a knob-like enlargement at its lower end adapted and positioned to engage the outer end of bar 18. Arm 27 has a split hub 27a embracing shaft 26 and clamped thereon by a screw 28. A collar 22 is secured to shaft 26, disposed between and engaging hub 27a and one side of the bearing arm 23. Another arm 29 is secured to shaft 26 and extends upwardly therefrom, arm 29 having a split hub 29a embracing shaft 26 and clamped thereto by a screw 30, said hub engaging one side of the bearing of arm 24. Endwise movement of shaft 26 is thus prevented. Arm 29 has a recess 29b adjacent its upper end for a purpose to be later described. A plate 31 extends vertically at the outer side of member 10 and this plate may be the front plate of a dispensing or similar machine. Plate 31 has an opening 31a adjacent its upper end and a bracket 32 is secured to the outer side of plate 31 by screws 33. Bracket 32 has flanges engaging plate 31 at either side of opening 31a and has an inwardly projecting plate 32a and an outwardly projecting plate or portion 32b. Bracket 32 has a slot extending through its inner and outer portions in which is slidably a coil slide 34. Slide 34 is in the form of a flat narrow plate and the same has an upturned cylindrical portion 34a at its outer end forming a handle. Slide 34 has a circular aperture 34b extending therethrough of a size to receive the proper coin to actuate the machine. Said member 34 also has a slot 34c some distance inwardly from aperture 34b adapted to receive the lower operating end of a pawl 35 pivoted on and carried on a stud 36 secured in a small boss 32c on bracket 32. Pawl 35 also has a tooth-like projection 35a extending through an opening in the top of bracket 32 and adapted to engage the side of an opening 34e in slide 34. A torsion spring 37 extends about stud 36 engaging bracket 32 with one of its ends and extending over and engaging pawl 35 with its other end. Bracket 32 has a laterally extending boss 32d receiving a stud 38 on which is carried a pawl 39 engaged by a tensile spring 40 secured to an arm thereof and at its other end to a projection 32e of bracket 32. Pawl 39 is adapted to engage certain recesses 34d formed in the side of slide 34. When slide 34 is pushed inwardly to the limit of its movement as indicated by dotted lines in Figs. 4 and 6, it engages in recess 29b of arm 29 to swing the same and shaft 26, thus swinging arm 27 to cause the latter to move bar 18.

Members 10 and 11 have another set of bosses

10b and 11b in which is journaled a shaft 42. Shaft 42 has secured thereto between said bosses a gear 43 having a hub engaging the ends of bosses 10bb and 11bb. Gear 43 has a cam 43a projecting at one side thereof beyond its hub, said cam having its operating face at its side portion, which side portion or surface extends circumferentially from the side of gear 43 to quite a distance laterally from said gear. Member 11 is provided with axially aligned inner and outer bosses 11f and 11g respectively in which is movable a plunger 44. Plunger 44 has a collar 44a within boss 11g engaged by a coil compression spring 45, the other end of which engages a collar 46 secured in the end of boss 11g so that plunger 44 is urged inwardly against cam 43a. Plunger 44 extends beyond the end of boss 11g and forms another operating element for the dispensing or similar machine with which the control device is used. In the embodiment of the invention illustrated the end of plunger 44 is shown as engaging a bell crank lever 47 mounted on a pivot 48 carried in a bracket 49 which will be secured to the frame of the machine. Bell crank lever 47 is shown as having a rod 50 pivotally secured to its other end which will perform some desired operation. A bar 51 extends between the members 10 and 11, having cylindrical trunnions 51a journaled in said members respectively. A pawl 52 extends laterally from bar 51 having a downwardly curved end adapted to engage between the teeth of gear 43 and prevent clockwise motion of gear 43 as seen Fig. 1. Pawl 52 is of considerable weight and acts by gravity in engaging gear 43. Reverse rotation of pinion 15 and gear 17 is also prevented when gear 43 is prevented from reverse rotation. A casing 55 of sheet metal extends over and about the sides of members 10 and 11 enclosing the parts therein, said casing being secured to member 10 by screws 56.

In operation when the machine is in position for dispensing an article, bar 18 will occupy the position shown in Fig. 5 and coin slide 34 will be in the position shown in full lines in Figs. 4 and 6. The party or operator desiring one of the dispensed articles will place a coin 54 in aperture 34b. There will be directions mounted on the machine telling the operator to deposit the coin and the denomination of the coin. The directions will also tell the operator how many turns to give the handle or crank 14. The operator having placed the coin in slide 34 will then push inwardly on said slide. The coin will move inwardly in bracket 32 and pawl 35 will be lifted as its curved end is engaged by slide 34 at the end of slot 34c. It will be noted that said pawl 35 will prevent slide 34 being moved outwardly or inwardly without a coin placed therein. Slide 34 is moved inwardly and must be moved to its innermost position before it can be retracted. When it moves to this position the end of pawl 39 enters the long recess 34d and can then reverse its position and allow slide 34 to be again moved outwardly to the full line position shown in Figs. 4 and 6. The coin slide comprising members 32 and 35 inclusive is well known in the art and forms no part of the present invention. When slide 34 is moved to its innermost position it engages arm 29 in recess 29b and arm 29 is swung to the dotted line position shown in Fig. 6. When arm 29 is thus swung shaft 26 is thus oscillated and arm 27 is moved to the dotted line position shown in Fig. 6 and bar 18 is moved to the position shown in Fig. 5. The operator can now revolve shaft 13 as directed. In the embodi-

ment of the invention illustrated shaft 14 will be given three rotations. Gears 17 and 43 will be rotated with pinion 15. Cam 43a will operate on plunger 44 and the mechanism operated by plunger 44 which is usually a trip operation will be performed. Shaft 16 will be rotated and the necessary operations of the machine performed by this shaft will be accomplished. As gear 17 nears the end of its revolution cam 17b will act on bar 18 engaging the same at one side of slot 18a and moving said bar to the position shown in Fig. 3. Just as said bar reaches this position or a moment after, stop 17a will engage the side of bar 18 and further rotation of shaft 13 or gear 17 will be prevented. In the embodiment of the invention illustrated there is a 3 to 1 ratio between gears 17 and 15 and gears 43 and 15. After the operator therefore, has turned shaft 14 for the directed number of revolutions the article will be dispensed and further rotation of said shaft will be prevented. The machine cannot again be operated until another coin is properly placed therein and slide 34 is again pushed inwardly. It will be noted that shaft 14 cannot be turned in the wrong or reverse rotation from that directed. Such reverse movement is prevented by pawl 52.

From the above description it is seen that applicant has provided a simple, rugged and efficient control mechanism for controlling the operation of a dispensing or other machine. The device is simple, the parts are few in number and all are rugged in construction and so mounted that there is no danger of any parts becoming disarranged or getting out of order. There is no delicate mechanism to be kept in adjustment. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

This application is a substitute for applicant's prior application S. N. 68,616, filed March 13, 1936, allowed December 24, 1936.

What is claimed is:

1. A control device for a dispensing machine having in combination, a rotatable member, means for rotating said member, a stop member movable with said member, a movable member movable to stop position to be engaged by said stop member and movable to non-stop position to permit passage of said stop member and rotation of said rotatable member, manually operated means for moving said movable member to non-stop position and means movable with said rotatable member to move said movable member to stop position.

2. A control device for a dispensing machine having in combination, a rotatable member, means for rotating said member, a stop member through which said member moves, movable to stop position to prevent rotation of said rotatable member and to non-stop position to permit rotation of said rotatable member and manually operated means for moving said stop member to non-stop position, said stop member being movable to stop position by said rotatable member.

3. A control device for a dispensing machine having in combination, a rotatable member, means for rotating said member, a stop member at one side of said member and carried thereby, a second member movable adjacent said rotatable member to stop position wherein said stop means engages the same and movable to non-stop position to permit passage of said stop means and rotation of said rotatable member, means for moving said second member to non-stop position and a cam on the other side of said rotatable member engaging said second member to move the same to stop position.

4. A control device for a dispensing machine having in combination, a shaft, a pinion thereon, a pair of gears meshing with said pinion, an operating shaft rotated by one of said gears, a stop means on said gear, a member movable to stop position with said means engaging the same and movable to non-stop position to permit passage of said means and rotation of said gear, means on said gear to move said member to stop position, manually operated means for moving said member to non-stop position, means engaging said other gear to prevent reverse rotation thereof and of said pinion and first mentioned gear and operating means movable by said other gear.

5. A control device for a dispensing machine having in combination, a rotatable member, a stop member carried by said rotatable member, a bar movable transversely of said member to stop position so that said stop member will engage the same and to non-stop position so that it will permit passage of said stop means and rotation of said rotatable member, manually operated means for moving said bar to non-stop position and a cam on said rotatable member for moving said bar to stop position.

6. The structure set forth in claim 5, said rotatable member constituting a gear and said bar having a slot through which said gear is movable.

7. A control device for a dispensing machine having in combination, a shaft, a pinion thereon, a gear meshing with said pinion and rotated thereby, means for limiting the number of rotations of said pinion comprising a stop means on said gear, a stop member engaged by said stop means, means for moving said stop member to non-stop position and means movable with said gear to move said stop member to stop position.

8. A control device for a dispensing machine having in combination, a casing, a shaft journaled in said casing, means for rotating said shaft, a pinion secured to said shaft, a second shaft journaled in said casing, a gear secured to said second shaft meshing with said pinion, a stop means on said gear, a bar extending transversely of said gear and having a slot therein through which said gear passes and through which said stop means may pass, means for moving said bar to stop position where it is engageable by said stop means, said bar being movable to non-stop position so that said stop means may pass through said slot and a cam on said gear engaging said bar at one end of said slot to move said bar to stop position after a certain rotation of said gear.

HENRY M. OLSEN.
